CLAIM

The ornamental design for a decorative broom handle, as shown.

DESCRIPTION

FIG. 1 is a front elevational view of a broom handle showing my new design;

FIG. 2 is a rear view thereof;

FIG. 3 is a left view thereof;

FIG. 4 is a right view thereof; and,

FIG. 5 is a top plan view thereof.

The broken lines showing bristles are illustrative purposes only and form no part of the claimed design. The bottom of the article neither shown in the drawing nor described in the specification forms no part of the claimed design.
